(57) **CLAIM**

The ornamental design for an auger system control unit, as shown and described.

DESCRIPTION

FIG. 1 is a perspective view of the present invention, with environmental structure that forms no part of the design to be patented, shown in broken lines;

FIG. 2 is a front elevational view of the present invention; FIG. 3 is a right side elevational view of the present invention;

FIG. 4 is a rear elevational view of the present invention; FIG. 5 is a left side elevational view of the present invention; and,

FIG. 6 is a top view of the present invention.
